UNITED STATES PATENT OFFICE.

WILLIAM T. HICKS, OF BLOOMINGTON, INDIANA.

MOLD FOR POSTS.

1,244,608.

Specification of Letters Patent. Patented Oct. 30, 1917.

Application filed March 16, 1915. Serial No. 14,776.

To all whom it may concern:

Be it known that I, WILLIAM T. HICKS, a citizen of the United States, residing at Bloomington, Monroe county, and State of Indiana, have invented and discovered certain new and useful Improvements in Molds for Posts, of which the following is specification.

In the construction of concrete posts for building fences and for other purposes, it is of advantage to have the exterior of the post of fine cement, impervious to water, and of a smooth and attractive finish, while, for the purposes of economy in manufacture the interior portions of the post may be composed of coarser material without impairing its strength or value for the purpose for which it is designed. Heretofore, this object has been accomplished by forming the interior part of the post of coarse material and surrounding said central part, or core, with a veneer of finer material. Such a post is illustrated in my former Patent No. 1,045,026, and a mold for making such post is illustrated in my former Patent No. 1,045,028.

The object of my present invention is to provide a molding apparatus for forming a post of the character described which may be employed in a manner to enable the result to be accomplished by a single operation and from a single mixture of concrete, and one which may be operated rapidly and conveniently at comparatively small expense, all as will be hereinafter more fully described and claimed.

Referring to the accompanying drawings, which are made a part hereof and on which similar reference numerals indicate similar parts,

Figure 1 is a central vertical section through my improved molding apparatus as assembled with the parts in operative position, and after the mold has been filled with concrete,

Fig. 2, a similar view with the top part of the interior shell removed,

Fig. 3, a side elevation of the interior shell, or grading member, assembled,

Fig. 4, a perspective view of the upper end of said grading member,

Fig. 5, a perspective view of one of the side sections of said grading member,

Fig. 6, a top end view, and

Fig. 7, a cross-section on the dotted line 55 7—7 in Fig. 1.

In said drawings like reference numerals indicate corresponding parts in the several figures of the drawings.

The outer shell 10 of the mold is substantially the same as that shown in my Patent No. 1,045,028, above referred to. It consists of a cylindrical mold, open at both ends and having one of its sides embodying a removable flat section 11, the parts being secured together by clamping bolts 12 extending through parallel out-turned flanges on the adjacent edges of the respective parts. Said shell is composed of sheet iron or other appropriate material. The lower end of the mold is filled by a disk 13, formed concave on its inner side to correspond with the desired shape of the top of the post.

The interior structure, which I have termed a "grading member," consists of two principal parts or devices, operating together to do and perform the desired work. The first, 14, is a short, hollow, open-ended cylindrical frustum, hereinafter called the cylinder, of a diameter slightly less than the post mold or outer shell, and of similar taper thereto, having oblong segments 15 fastened to the cylinder at equidistant points around the larger and outer circumference, such segments extending in a longitudinal direction, with their outer edges slightly raised above the cylinder barrel, so as to form grooves or recesses to receive the tongues or tenons of the perforated grading sections.

The principal office of the cylinder is to space and hold in proper place the perforated grading sections while the latter are being placed in the mold, and to further securely hold them until a partial filling in of the concrete relieves the necessity, when the cylinder is withdrawn. Said grading member is further composed of sections 16, being long, thin, tapering, flexible, curved, metal plates, numerously perforated, having tongues or tenons 17 at their upper ends, adapted to slide into the grooves or recesses on the cylinder 14. There are several of these sections 16, enough, allowing something for overlapping, to complete the cir-

cle. The edges of each alternate section are turned outwardly slightly to form spacing ridges 20 between the outer shell 10 and the outer surface of said grading member. 5 Other spacing members 18 may be interposed such as small longitudinal ribs crimped in the perforated plates, or a rod fastened vertically thereto. Such rods or ribs 18, and the turned out edges 20, serve 10 to support and steady the grading members and space the same at a proper distance from inner wall of the outer shell 10. The upper end of cylinder 14 of said grading member extends for a distance to within the 15 sections 16 and serves to prevent them from collapsing. At intervals around the cylinder 14, on its inner face, are mounted sockets 21 for receiving and supporting reinforcing rods 22. Said rods are supported 20 by small hooks, or other appropriate means at their upper ends, so as to prevent their lower ends from approaching too close to the surface of the disk 13 and projecting through the cement forming the upper end 25 of the post. The sockets 21 are of sufficient size so that said hook ends may pass through when the grading member is removed, leaving said reinforcing rods embedded in the concrete. Other reinforcing members, 30 such as the spirally wound basket of my Patent No. 1,045,026, may be adapted for use with this mold, if preferred.

Each of the sections 16, as clearly shown in the drawings, is formed with numerous 35 perforations, said perforations being of a size to permit the fine semi-liquid concrete to run through them. The space between the outer wall 10, and the grader wall is so narrow or thin that no coarse material can 40 get through or occupy it, but such stuff will strike the outer wall before clearing the perforations, and will be forced back toward the interior during the process of withdrawing the perforated plates and completely covered by the fine concrete. 45

In operation, the parts are assembled as shown in Fig. 1, the reinforcing rods 22 being in place and supported above the disk 13 for a short distance, as shown. A small 50 quantity of fine concrete is first deposited on the upper surface of disk 13 to form the top surface of the post. The concrete mixture is then poured into the top through the interior of cylinder 14. Sufficient of the 55 fine, or semi-liquid cement, will percolate through the perforations in the members 16, into the space between said members and the outer shell 10, to fill said space. After the grading member has been filled to near 60 the top, the cylinder member 14 is withdrawn by hooking suitable lifting tackle (not shown) into appropriate ears or holes 23 formed in its sides. The rods 22 are turned so that their hooks will pass through 65 the sockets 21, allowing said rods to re-

main embedded in the concrete. The members 16 are then withdrawn by hooking suitable lifting tackle into appropriate ears, or eyes, 24 in the upper ends thereof. The concrete then settles in the mold, the fine 70 concrete being packed against the interior of the outer shell 10. The concrete is allowed to dry or cure. After it is cured or "set," the outer shell may be removed by 75 loosening the clamping bolts 12.

By this apparatus, a concrete post is formed, having a smooth and fine-grained outer surface which will be impervious to moisture and will also be attractive in finish, while the interior of the post may be 80 composed of inexpensive, coarse material, appropriately reinforced, which will afford the necessary strength and rigidity for such a post as desired. It will be understood, of course, that the concrete mixtures may vary 85 in accordance with the character of the post being manufactured. Posts for some purposes may be made of a larger proportion of the coarse inexpensive material than others, and without in any manner impairing the efficiency of the product. The operation of the mold requires no skill or experience, it being simple in structure and easy to assemble and dismantle as will be 90 readily seen.

While I have described this mold as for the manufacture of concrete posts, it will be understood, of course, that it may be adapted for other uses for which it may be found appropriate, all such uses and modifications being within the scope of my invention and intended to be included within the meaning of the terms used herein.

It will be understood, of course, that various modifications in the details of construction may be made without departing from the spirit and scope of my invention as defined in the following claims.

Having thus fully described my said invention, what I claim as new and desire to 110 secure by Letters Patent, is:

1. A mold for concrete posts comprising an outer imperforate shell and an inner shell having walls with openings therein and composed of longitudinal sections and an upper end section through which the concrete is admitted, substantially as set forth.

2. A mold for forming concrete posts comprising an outer imperforate shell, and inner perforated shell made up of sections and spaced a distance therefrom, and an end section for said inner shell adapted to receive a concrete mixture and formed to be removed after said concrete mixture is 120 deposited therein, substantially as set forth.

3. A mold for forming concrete posts comprising an outer shell having an imperforate wall and a closed lower end, an inner shell with perforated walls and open at 125 130

both ends, and an upper end section formed for connection with said inner shell and adapted to receive the concrete mixture, said interior shell being formed in sections 5 and to be removed after said concrete mixture has been deposited therein, substantially as set forth.

4. A mold for forming concrete posts, comprising an outer shell, a grading member within said outer shell formed of perforated sections, a cylindrical upper end section detachably mounted on said perforated sections, and means for spacing said grading member from said outer shell, said 10 grading member being formed to be removed after the concrete has been deposited therein, substantially as set forth.

5. A mold for forming concrete posts comprising an outer shell, a perforated 20 grading member mounted within and spaced from said outer shell, said grading member being formed in sections and attached to a hollow cylindrical upper end and having therein means for temporarily suspending 25 and supporting reinforcing members, substantially as set forth.

Copies of this patent may be obtained for five cents each, by addressing the "Commissioner of Patents, Washington, D. C."

6. A mold for forming concrete posts comprising an outer shell and an inner perforated grading member, said grading member comprising a hollow cylindrical 30 end and several sections detachably secured thereto, each of said sections being formed with means for spacing said member from the outer shell, substantially as set forth.

7. A mold for forming concrete products 35 comprising an outer shell, and a grading member formed of longitudinal sections joined at their edges and adapted as a whole to coöperate with and for use within said outer shell having perforated walls spaced 40 a distance from said outer shell and formed to be removed after the concrete mixture is deposited therein, substantially as set forth.

In witness whereof, I have hereunto set my hand and seal at Bloomington, Indiana, 45 this 11th day of March, A. D. nineteen hundred and fifteen.

WILLIAM T. HICKS. [L. S.]
